UNITED STATES PATENT OFFICE.

ELIAS R. WILNER, OF NEW YORK, N. Y.

INCANDESCENT GAS-LAMP.

No. 874,716.

Specification of Letters Patent.

Patented Dec. 24, 1907.

Application filed April 5, 1906. Serial No. 309,960.

To all whom it may concern:

Be it known that I, ELIAS R. WILNER, a citizen of the United States, and a resident of the borough of Manhattan, city, county, and State of New York, have invented certain new and useful Improvements in Incandescent Gas-Lamps, of which the following is a specification.

My invention relates to incandescent gas lamps, and has for its object to provide a lamp of this description which may be used as an upright lamp or as an inverted lamp.

Other objects of my invention will appear from the annexed description, and the features of novelty will be pointed out in the appended claims.

Reference is to be had to the accompanying drawing in which

Figure 1 is an elevation with parts in section showing my improved lamp as an inverted light; Fig. 2 is a plan view thereof partly in section and Fig. 3 is a detail sectional view on the line 3—3 of Fig. 2.

A is the burner tube to the free end of which is attached the usual mantle B. The said mantle B is carried by the usual ring B', which in the present case is supplied with fingers or lugs B². These lugs B² are adapted to engage a support B³ which is removably secured to the burner tube A. The support B³ is provided with arms B⁴ having open slots B⁵ into which the lugs B² are adapted to enter, the bent over portions of said lugs B² thus supporting the mantle in proper position on the burner tube A. It is to be understood that the lugs B² of the ring B' first engage the support B³ with the bent over portions of the lugs B² in the spaces between the arms B⁴, after which the ring B' is then given a partial turn so that the lugs B² enter the open slots B⁵ in the manner of a bayonet joint. The burner tube A is in communication with a mixing chamber C provided with air inlets D. A shutter E provided with openings E' is arranged to rotate about the outside of said mixing chamber for the purpose of regulating the amount of air to be admitted to the mixing chamber C. This regulation of the air is accomplished by turning the shutter E so that the air inlets are more or less covered thereby, the maximum amount of air being admitted to the mixing chamber when the openings E' are in perfect registry with the air inlets D. The mixing chamber C is attached by means of screw-threads to the support F which in turn is screwed on the

customary gas fixture at F'. To regulate the amount of gas which enters the mixing chamber, the support F is provided with a needle valve G adapted to engage the seat G' in a portion of the support F which extends into the mixing chamber. The needle valve is operated by turning the knob or handle G² and is secured in any position by means of the lock nut G³. By thus providing for the regulation of the air and gas which enters the said mixing chamber C before it reaches the burner tube A, the most efficient mixture is secured, to give the best illumination, without any undue waste of gas.

In connecting my lamp with the usual gas fixture, which I have not deemed it necessary to show, the support F is first screwed on said fixture, after which the mixing chamber C is screwed on said support at C'.

In many cases the extent of the screw threads will vary so that when the lamp has been attached to the support F in the manner just described, the burner tube A with the mantle attached thereto will be found to stand at an angle.

To overcome this objection I provide a screw-threaded collar H which is in screw-threaded engagement with the support F as shown in Figs. 1 and 2, so that when the lamp is screwed on said support a sufficient

distance to hold it (in the present illustration, with the burner extending downwardly) the collar H is then screwed up tight against the mixing chamber C, thus securely holding the lamp in position.

If it is desired to use the lamp as an upright lamp, or in other words in the reverse position from that shown in the drawings, this collar H is loosened and the lamp turned so that the burner tube extends upward, after which the collar H is again screwed up against the mixing chamber C.

The lamp is thus securely held in position for use as an upright lamp. To prevent the mantle from being dislocated by this change in position of the burner tube, in case the mantle connection with said tube is a loose one, the tube A is screw-threaded a part of its distance as shown at A' to accommodate a nut I.

This nut I is adapted to be screwed up against the mantle ring and thus prevents the mantle from dropping out of position when the lamp is used in the upright position.

The globe J is secured in place in the supporting ring K in the customary manner by means of screws L. The supporting ring K is held in place by the member M which is se-

cured to the burner tube by means of rivets M' and is provided with two arms M² which are secured to the ring K by rivets or screws M³, and form a yoke over the burner tube A. 5 To steady the ring K and prevent it from sagging, the member M has an additional arm M⁴ secured to the ring K at a point substantially opposite to the point where the arms M² are fastened as at M⁵. This construction 10 results in a very rigid support for the globe, which support is also easily attached in position.

15 Various modifications may be made without departing from the nature of my invention as defined in the claims.

I claim:

1. An incandescent gas lamp capable of being adjusted either to an upright or an inverted position, means for securing said lamp 20 in either position, and means for retaining the mantle in proper location in either position of the lamp.

2. In an incandescent gas lamp, a burner

25 tube, a mantle supported adjacent to the free end of said burner tube, a mixing chamber in communication with said burner tube, means for regulating the amount of air which enters said mixing chamber, and means for regulating the amount of gas which enters said mixing chamber, said gas regulating 30 means being in close proximity to the air regulating means.

3. An incandescent gas lamp capable of being adjusted either to an upright or an inverted position, a lock-nut for retaining said lamp in either position and another lock-nut for securing the mantle in proper location in either position of the lamp.

40 In testimony whereof, I have hereunto signed my name in the presence of two subscribing witnesses.

ELIAS R. WILNER.
